GYRO-CONTROLLED STABILIZING SYSTEM

John W. Dawson, West Newton, Mass., assignor
to Raytheon Manufacturing Company, Newton,
Mass., a corporation of Delaware

Application January 3, 1944, Serial No. 516,896

14 Claims. (Cl. 318—19)

1
This invention relates to a stabilizing system for maintaining the position of an object, such as a directionally radiating antenna, aimed in a predetermined direction under conditions in which the support for such an object, such as a deck of a ship, may be subjected to a haphazard variation in its position.

An object of this invention is to devise such a stabilizing system which is simple, rugged and reliable.

Another object is to devise such a system in which a gyroscope mounted in gimbals, directly and mechanically stabilizes the position of a second gimbal system on which the stabilizing control elements are mounted.

A further object is to devise a simple lever arm arrangement for connecting the two gimbal systems in such a way that one of said gimbal systems may rotate freely with respect to the other.

A still further object is to incorporate in such a system an angle computing mechanism which introduces a correction into the azimuthal position of the controlled object, which compensates for the tilt of the carrier of the controlled object, such carrier being, for example, the deck of a ship.

The foregoing and other objects of this invention will be best understood from the following description of exemplifications thereof, reference being had to the accompanying drawings wherein:

Fig. 1 is a diagram of one form of my invention applied to an arrangement for maintaining the line of sight of the controlled object fixed on the horizon in a predetermined azimuthal angle;

Fig. 2 is a circuit diagram of one portion of the arrangement shown in Fig. 1;

Fig. 3 is a circuit diagram of another portion of the arrangement shown in Fig. 1; and

Fig. 4 is a diagram of another form of angle computer for my invention as applied to an arrangement for maintaining the line of sight of the controlled object at a fixed azimuthal angle and at a fixed angle of elevation about the horizon.

In the arrangement shown in Fig. 1, a controlled object 1, such as a directional radiating antenna system for radiating super-high frequency waves, is to be controlled so as to maintain its line of sight intersecting a fixed point on the horizon. The controlled object, which is mounted in a frame 2, is fixed to a pair of shafts 3 which are rotatably mounted in the side portions of said frame member. The shafts 3 establish an axis which is termed the tilting axis of

the controlled object 1. The frame 2 is mounted on a vertical shaft 4 which is driven by a motor 5 supported on a base 6 which is fixed to some movable carrier, such as a deck of a ship or the like. The axis of rotation of the vertical shaft 4 is herein termed the azimuthal axis.

The controlled object 1, which may be set with its line of sight intersecting a predetermined point on the horizon by means which will be described 10 below, is maintained in its set position despite the pitch and roll of the ship upon which it is mounted by the action of a stabilizing system. This stabilizing system includes a gyroscope 7 of the self-erecting type mounted in gimbals including a frame member 8 fixed to a supporting base 9, likewise mounted upon the same carrier which carries the supporting member 6. The gimbals also include a ring member 10 in which the gyroscope 7 is pivoted on pivots 11. The ring member 10 is in turn pivoted to the frame member 8 at pivots 12. The axis extending through the pivots 12 is substantially at right angles to the axis extending through the pivots 11.

Associated with the gyroscope 7 is an angle computer mechanism 13 which includes a synchro 14. The synchro 14 comprises a frame member 15 within which is contained an armature member carried by a shaft 16 rotatable in the frame member 15. The right hand portion of Fig. 2 illustrates diagrammatically the interior connections of the synchro 14. In Fig. 2, 17 represents a closed winding carried by the frame member 15. The shaft 16 carries an armature 18, upon which is provided a winding 19. Referring again to Fig. 3, 1, the frame member 15 is fixed upon a pair of shafts 20 which are rotatably mounted in a ring member 21 of another gimbal system. The ring member 21 is pivoted to a frame member 22 about an axis substantially perpendicular to the axis extending through the shafts 20. The frame member 22 is mounted on a vertical shaft 23 which is rotatably supported in a bearing member 24 fixed to the support 9. The top of the gyroscope 7 is provided with a pair of arms 25 fixed to and projecting upwardly from said gyroscope. If desired, a cross arm 26 may be provided to brace the upper portions of the arms 25. A pair of tie rods 27 is pivoted respectively to the upper ends of the arms 25. The other end 50 of each of the tie rods 27 is pivoted to the upper end of the shaft 16 in such a way that said shaft 16 cannot rotate about its longitudinal axis with respect to the tie rods 27. The frame member 22 may be rotated about its vertical or azimuthal axis by motor 28 which is geared to the shaft 23

by gears 28 and 30, the gear 30 being fixed on the shaft 23. The motor 28 is energized from a pair of output conductors 31 of a suitable servo amplifier 32 supplied with power from a pair of leads 33 connected to a suitable source of alternating current. The servo amplifier 32 may be of the type as described and claimed in my copending application, Serial No. 509,631, filed November 9, 1943, now Patent 2,423,438, dated July 15, 1947, in which the magnitude and direction of the voltage supplied to the leads 31 are dependent upon the magnitude and phase of a control voltage supplied to the input conductors 34 of the servo amplifier. In the present arrangement the conductors 34 are connected to the ends of the armature winding 18 of the synchro 14. Thus it will be seen that the output signal from the synchro 14 will control the speed and direction of rotation of the motor 28. Under these conditions the motor 28 drives the frame member 22 and thus the frame member 15 of the synchro 14 to a position in which the armature 18 is at right angles to the magnetic field of the winding 17, under which conditions substantially no output signal voltage is supplied to the conductors 34. This position of the armature 18, with respect to the magnetic field of the winding 17 may be termed the "zero position" of the synchro 14. The position of the magnetic field of the winding 17 is controlled in a manner to be described below by a compass synchro 35 which feeds into an azimuthal control differential synchro 36 which in turn feeds into the winding 17 of the synchro 14.

A synchro 37 is associated with the angle computer mechanism 13 to transmit the proper azimuthal control to the controlled object 1. The synchro 37 is provided with a frame-member 38 fixed to the support 9 and with an armature member mounted on a rotatable shaft 40. The shaft 40 has secured thereto a gear 41 which engages with the gear 30 fixed to the shaft 23. The synchro 37 feeds into a synchro 42 having a frame member 43 fixed to the support 6 and an armature mounted on a rotatable shaft 44. The shaft 44 is geared by means of gears 45 to the shaft 4. A signal voltage, developed in the synchro 42 as will be explained below, is fed through a servo amplifier 46, similar to the servo amplifier 32, and by output conductors 47 extending from the servo amplifier 46, to the motor 5. The servo amplifier 46 is supplied with power from leads 48 preferably connected to the same source of alternating current as the leads 33 of servo amplifier 32.

The tilting of the controlled object 1 about its tilting axis is controlled by a synchro 49 whose frame member 50 is fixed to the frame member 22 of the angle computer 13. The synchro 49 is likewise provided with an armature mounted on a rotatable shaft 51 to which is fixed a gear 52. The gear 52 meshes with a rotatable gear 53 carried by an arm of the frame member 22 and rotatable thereon. The gear member 53 engages with a gear 54 fixed to and rotatable with the ring member 21, as said ring member rotates about its horizontal axis which is at right angles to the axis of the shafts 20. Thus, tilting of the ring member 21 about said horizontal axis will produce a corresponding rotation of the shaft 51 and the armature of the synchro 49 mounted thereon. The output of the synchro 49 feeds into a synchro 55 whose frame member 56 is fixed to the frame 2. The synchro 55 is likewise pro-

vided with an armature mounted upon the shaft 3 which also carries a gear 57. Said gear 57 meshes with a gear 58 carried upon the shaft of motor 59 whose frame is likewise fixed to the frame 2. The signal voltage generated within the synchro 55 is fed by means of a pair of leads 60 to a servo amplifier 61, the output of which is fed by means of conductors 62 to the motor 59. The servo amplifier 61 is similar to the servo amplifier 32 and is likewise supplied with power from a pair of leads 63 which are preferably connected to the same source of alternating current as the leads 33 of the servo amplifier 32.

Certain aspects of the operation of the system shown in Fig. 1 will be more clearly understood by referring to the electrical diagram in Fig. 2. As illustrated in this figure, the compass synchro 35 comprises a closed stator winding 64 which is mounted upon a suitable stator member fixed to and carried by the ship. The compass synchro 35 also is provided with a rotatable armature 65 carrying an armature winding 66 supplied with exciting alternating current through a pair of leads 67 connected to the same alternating current source as the leads 33 of the servo amplifier 32. The armature 65 is adapted to be rotated by a compass card 68 which thus maintains the armature 65 in a predetermined azimuthal position, usually a north and south position, as the stator winding 64 moves with changes in the position of the ship. The differential synchro 36 associated with the compass synchro 35 is likewise provided with a stator winding 69 carried by a suitable stator member. The differential synchro 36 is also provided with an armature 70 rotatable in the field of the stator winding 69 and carrying a closed armature winding 71. Three equally-spaced points on the winding 71 are connected to three corresponding slip rings 72 upon which bear brushes connected to three conductors 73 extending to three similarly equally-spaced points 73' on the stator winding 64 of the compass synchro 35. The armature 70 is rotated with respect to the winding 69 by means of a controlling member 74, such as a hand-crank. Of course it is to be understood that this controlling member may take any other form which is well known in position control systems. Three equally-spaced points 75 on the stator winding 69 are connected by means of conductors 76 to three similarly equally-spaced points 77 on the winding 17 of the synchro 14.

The alternating current field of the armature 65 induces voltages in the stator winding 64 which are transmitted by the conductors 73 to the armature winding 71 and reproduce a magnetic field in the space within the stator of synchro 36 which has the same angular orientation with respect to the three points on the winding 71 connected to the slip rings 72 as the three points 73' have with respect to the position of the armature 65. Thus, as the stator winding 64 turns with respect to its armature 65, the field reproduced by the winding 71 will likewise turn with respect to said winding 71 to the same angular extent as the stator winding 64 turns with respect to its armature 65. When the controlling member 74 physically turns the winding 71, such motion is superposed on the above described motion of the field 71, and thus the absolute motion or position of the field created by the armature winding 71, with respect to its stator winding 69, is the resultant of the motion of the winding 64 and of the controlling member 74. The alternating field created by the armature winding 71

will induce voltages in its associated stator winding 68, which voltages are transmitted by the conductors 78 to the winding 17 of synchro 14. This will reproduce a magnetic field within the synchro 14 which bears the same angular relationship to the three points 77 on the winding 17 as the magnetic field of the winding 71 bears to the three points 75 on the winding 69. Unless the armature 18 is substantially at right angles to the field of the winding 17, a signal voltage will be generated in the winding 18. This voltage will be a measure of the deviation of the armature 18 from its desired zero position. This signal voltage, as already described, when fed to the servo amplifier 32 causes a current of the proper magnitude and direction to be supplied to the motor 28 so as to drive the winding 17 to a position in which the armature 18 is at right angles to the magnetic field of the winding 17.

Upon referring to Fig. 1, it will be seen that the above described motion produced by the motor 28 is imparted to the frame member 22 about the vertical axis of the shaft 23. It is desired that this motion likewise be transmitted to the controlled object 1 so as to control its azimuthal position. This action will be more clearly understood by referring to Fig. 3 which represents the electrical circuit between the synchros 37 and 42, together with the associated motor 5. The synchro 37 is provided with a closed stator winding 78 carried by the frame member 38 of the synchro 37. Said synchro 37 is also provided with an armature 79 carried by the shaft 40. The armature 79 is provided with a winding 80 which is supplied with alternating current from a pair of lead-in conductors 81 which are connected to the same source of alternating current as the conductors 48 of the servo amplifier 46. Three equally-spaced points on the winding 78 are connected to three equally-spaced points on the stator winding 82 of the synchro 42. The stator winding 82 is carried by the frame member 43 of said synchro 42. The synchro 42 is also provided with an armature 83 carried by the shaft 44, which as already described is driven by the motor 5 through a suitable gear drive 45. The armature 83 is likewise provided with a winding 84 which delivers a signal voltage through the conductors 85 to the servo amplifier 46. As is well known in such a synchro system, the field of the armature 79 will be reproduced by the winding 82 of the synchro 42, and the signal voltage delivered by the leads 85 will be a measure of the deviation from the desired zero position of the armature 83 in which said armature is at right angles to the magnetic field of the winding 82. Under these conditions the servo amplifier 46 will supply current of proper magnitude and polarity to the motor 5 so as to drive the armature 83 to its zero position.

The tilting of the controlled object 1 is controlled by the synchros 49 and 55 and by the associated motor 59. The circuit of the synchros 49 and 55 and their associated motor 59 is identical with the circuit arrangement of the synchros 37 and 42 and their associated motor 5. Therefore the arrangement as shown in Fig. 3 and the description given above in connection therewith apply with equal changes to the synchros 49 and 55 and their associated motor 59. Thus it will be seen that as the armature of the synchro 49 is turned by the shaft 51, motor 59 will drive armature of synchro 55 to its zero position and produce a corresponding tilting of the controlled object 1 about the axis of its shaft 3.

For purposes of analysis we may assume that, at a particular time, the ship carrying the above described stabilizing system is motionless and the controlled object 1 is set with its line of sight intersecting a point on the horizon. In order to set the line of sight of the object 1 in some other predetermined azimuthal angle, the controlling object 74 is rotated through the desired angle and this rotation is transmitted through the synchros 36 and 14 to cause the motor 28 to drive the frame 22 through the same angle. This angular motion is transmitted through synchros 37 and 42 causing motor 5 to drive the frame 2 through the same angle and thus the controlled object 1 is set in the desired azimuthal position as fixed by the setting of the controlling object 74. If the ship changes its azimuthal position, the compass synchro 35 will cause its armature 85 to move through the same angle as that through which the ship moves. This angle will be transmitted through synchros 35, 36 and 14 to cause motor 28 to drive the frame 22 through the same angle. This motion in turn will be transmitted through synchros 37 and 42 and their associated motor 5 to the frame 2. Thus having once fixed the controlled object 1 with its line of sight in a predetermined azimuthal angle, the compass synchro 35 will compensate for all azimuthal variations in the position of the ship and cause the controlled object 1 to be maintained with its line of sight in said predetermined azimuthal position.

As the ship pitches and rolls the gyroscope 1 will maintain the arms 25 in a vertical plane and the connection to the shaft 16 by means of the tie rods 27 will likewise maintain the shaft 16 in a vertical plane and will also prevent said shaft from twisting about its own longitudinal axis with respect to the tie rods 27. If the ship tilts in a plane parallel to the vertical plane containing the line of sight of the controlled object 1, the shaft 16 remaining vertical will cause the frame 22 to tilt with respect to the ring 21. The angle through which such relative motion occurs will be transmitted through the gear train 52, 53, 54 to the shaft 51 which will therefore rotate the armature of the synchro 49 through the same angle. The motion of the armature of the synchro 49 will transmit said angle to the synchro 55 and therefore motor 59 in driving the armature of synchro 55 to its zero position will likewise impart the same angle of motion to the controlled object 1. It will be seen therefore that the above described tilting of the ship will be compensated for by the tilting of the controlled object 1 about its tilting axis whereby the line of sight of said controlled object will be maintained fixed on the horizon.

If the ship tilts in a plane parallel to a vertical plane at right angles to the line of sight of the controlled object 1, no compensation is needed. Under these conditions the ring 21 and the frame 22 as a unit will tilt about the axis of the shafts 20. As will be noted, this does not shift the settings of any of the synchros and thus no compensation will be introduced into the system under these conditions.

If the ship tilts in a plane at an angle to either of the above defined vertical planes, the synchro 49 will transmit the component of that tilt which occurs in the vertical plane containing the line of sight of the controlled object 1 and will discard the component which lies in the vertical plane at right angles to said line of sight. Tilting of the ship in the last defined direction requires an

additional degree of azimuthal compensation in order for the line of sight of the controlled object 1 to be maintained in the desired direction. Such an azimuthal compensation is introduced directly by the synchro 14. If the ship moves in the last defined manner, a twist will occur between the stator 15 and the shaft 16 of the synchro 14. The angle of this twist will be exactly equal to that which must be imparted to the azimuthal position of the controlled object 1 to keep its line of sight fixed in its desired azimuthal angle and intersecting the horizon. As described above such a relative angular motion between the shaft 16 and its stator 15 will cause motor 5 to introduce an equal angular shift in the azimuthal position of the controlled object 1.

The total result of the above described compensations is that the line of sight of the above controlled object 1 may be fixed by the controlling member 74 on any predetermined azimuthal point on the horizon and said line of sight will be maintained at that point irrespective of any motion of the ship.

Since in the above-described system the synchros 35, 37, and 49 transmit an angular position from one point to a relatively remote point, synchros of this type may be termed transmitting synchros. The synchros 14, 42, and 55 receive signal currents from the transmitting synchros and therefore may be termed receiving synchros. Synchro 36 receives signal currents from transmitting synchro 35 and superimposes upon the angular position thus established an additional angular position as determined by the controlling member 74. For this reason synchro 36 represents a type which may be termed a differential synchro. Since synchro 36 also transmits the resultant angular position to the synchro 14, such a differential synchro can also be considered as a type of transmitting synchro.

In some cases it is desirable to keep the line of sight of the object 1 fixed in a predetermined azimuthal position with a fixed angle of elevation above the horizontal. An angle computer for accomplishing the foregoing is shown in Fig. 4 in which the same reference numerals as occur in Fig. 1 are applied where the elements are identical with those of Fig. 1. In Fig. 4 synchro 14 is carried on its shafts 20 rotatably mounted in an inner ring member 86. This inner ring member is carried rotatably by shafts 87 and 88 mounted in an outer ring member 21. The axis of the shafts 87 and 88 is substantially perpendicular to the axis of shafts 20. The outer ring member 21 is pivoted, as described in Fig. 1, to the frame member 22 along an axis substantially at right angles to the axis of shafts 20 and substantially parallel with the axis of shafts 87 and 88. The shaft 88 is geared by gears 89 and 90 to the rotor of a synchro 91. This synchro is substantially identical with the synchro 42 as described in connection with Figs. 1 and 3. The synchro 91 has a stator 92 which is fixed to the ring member 21. The input to the synchro 91 is supplied from a synchro 93 which is substantially identical with synchro 37 described in connection with Figs. 1 and 3 except that the position of its armature is controlled by a suitable controlling member 94 of the same type as the controlling member 74. The synchro 93 is provided with input leads 95 connected to a source of alternating current which is the same as that connected to the leads 63 of the servo amplifier 61. The synchro 93 is also provided with input leads 96 leading to the stator of synchro 91. The

signal voltage developed in the synchro 91 is fed through output leads 97 to a servo amplifier 88, similar to servo amplifier 32. The servo amplifier 88 is supplied with power from leads 98 connected to the same alternating current source as the leads 85 of the synchro 93. The output of the servo amplifier 88 is fed through leads 100 to a motor 101, the frame of which is fixed to the outer ring member 21 and the rotor of which drives a gear 102, engaging with the gear 88. Thus by actuation of the controlling member 94, the motor 101 will introduce a predetermined angular displacement between the inner ring member 86 and the outer ring member 21. This angular displacement will likewise be transmitted to the synchro 49 through the gear train 84, 53, 52.

A system incorporating the angle computer of Fig. 4 operates the same as does the system Fig. 1, except that the controlled object may be given a predetermined angle of elevation above the horizontal and maintained with its line of sight in said elevation. The angle of elevation is fed into the system by the controlling object 94 which will cause the outer ring member 21 to tilt with respect to the inner ring member 86 through the desired angle of elevation which, as previously described, is transmitted to the synchro 49. The synchro 49 will then transmit the angle to the synchro 55 and its associated motor 58 (Fig. 1) and thus cause the controlled object 1 to tilt about its tilt axis through the desired angle of elevation. Once the angle of elevation of the controlled object 1 is set in this way, the system thereafter operates to stabilize the position of the controlled object 1 in exactly the same manner as described in connection with Figs. 1-3.

From the foregoing it will be seen that with the arrangement as shown in Fig. 4, the controlled object 1 may be set with its line of sight in a predetermined azimuthal angle at a predetermined elevation above the horizontal and such setting will be automatically maintained despite any motion of the ship.

Of course it is to be understood that this invention is not limited to the particular details as described above as many equivalents will suggest themselves to those skilled in the art. For example, although I have described the transmission of an angular position as occurring in each case between a single pair of synchros, other well known arrangements for increasing the speed and accuracy of such transmission may be utilized. One preferred arrangement is to use for each angular transmission a pair of transmitting synchros, one of which is geared to the angularly moving member by a gear ratio which multiplies the rotational speed. A similar geared pair of receiving synchros is associated with the transmitting synchros and a relay is utilized so that the high speed transmitting and receiving synchros are utilized for the major travel and the low speed transmitting and receiving synchros are utilized for the final fine adjustment. Since such a system is well known it has not been illustrated herein in the interest of simplicity and clarity. Also other types of angle transmitting systems may be utilized. Thus as used in the claims the term "synchro" is intended to be understood in a generic sense to cover those devices which have a pair of relatively rotatable members and which function to transmit or receive angular or rotational values. Various other equivalents which utilize the principles of the in-

vention enunciated herein will suggest themselves to those skilled in the art.

It is accordingly desired that the appended claims be given a broad interpretation commensurate with the scope of the invention within the art.

What is claimed is:

1. In a position stabilizing system, an object whose position is to be stabilized, a controlled gimbal system, said gimbal system comprising a frame member, a ring member, and a reference member, said reference member having two relatively rotatable component parts, one of the component parts of said reference member being rotatable in said ring member about a ring axis fixed with respect to said ring member, the other component part of said reference member being rotatable about an axis substantially perpendicular to said ring axis, said ring member being rotatable in said frame member about a frame axis angularly disposed with respect to said ring axis and fixed with respect to said frame member, control means having a reference member maintained in a predetermined reference plane, a linkage connecting said last-named reference member to said last-named component part and maintaining said axis of said last-named component part in fixed angular relation to said last-named reference member in a plane substantially at right angles to said last-named reference member and passing through said last-named reference member and said last-named axis, said last-named component part being fixed to said linkage to prevent rotation of said last-named component part with respect to said linkage about said last-named axis, and means for transmitting the angular changes between said component parts to said object.

2. In a position stabilizing system, an object whose position is to be stabilized, said object being movable about two axes angularly disposed relative to each other, a controlled gimbal system, said gimbal system comprising a frame member, a ring member, and a reference member, said reference member having two relatively rotatable component parts, one of the component parts of said reference member being rotatable in said ring member about a ring axis fixed with respect to said ring member, the other component part of said reference member being rotatable about an axis substantially perpendicular to said ring axis, said ring member being rotatable in said frame member about a frame axis angularly disposed with respect to said ring axis and fixed with respect to said frame member, control means having a reference member maintained in a predetermined reference plane, a linkage connecting said last-named reference member to said last-named component part and maintaining said axis of said last-named component part in fixed angular relation to said last-named reference member in a plane substantially at right angles to said last-named reference member and passing through said last-named reference member and said last-named axis, said last-named component part being fixed to said linkage to prevent rotation of said last-named component part with respect to said linkage about said last-named axis, driving means responsive to the movement of the ring member of the controlled gimbal system relative to its frame member about its frame axis for moving said object about one of its axes through an angle substantially equal to the angle of motion between said controlled gimbal system ring and frame member, and driving means responsive

to a change in the angular relation between said component parts for moving said object about its other axis through an angle substantially equal to said change in angular relation between said component parts.

3. In a position stabilizing system, an object whose position is to be stabilized, said object being movable about two axes angularly disposed relative to each other, a controlled gimbal system, said gimbal system comprising a frame member, a ring member, and a reference member, said reference member comprising a synchro having two relatively rotatable component parts, said component parts being electrically energized to produce an output signal which varies with variations in the angular relation between said component parts, one of the component parts of said reference member being rotatable in said ring member about a ring axis fixed with respect to said ring member, the other component part of said synchro being rotatable about an axis substantially perpendicular to said ring axis, said ring member being rotatable in said frame member about a frame axis angularly disposed with respect to said ring axis and fixed with respect to said frame member, control means having a reference member maintained in a predetermined reference plane, a linkage connecting said last-named reference member to said last-named component part and maintaining said axis of said last-named component part in fixed angular relation to said last-named reference member in a plane substantially at right angles to said last-named reference member and passing through said last-named reference member and said last-named axis, said last-named component part being fixed to said linkage to prevent rotation of said last-named component part with respect to said linkage about said last-named axis, a second synchro having two relatively rotatable component parts of which one is fixed to said frame member and the other rotatable with said ring member, the component parts of said second synchro being likewise electrically energized to produce an output signal which varies with variations in the angular relation between said component parts, means responsive to one of said output signals to move said object about one of its axes in accordance with the variation in said output signal, and means responsive to the other of said output signals to move said object about the other of its axes in accordance with the variation in said other output signal.

4. In a position stabilizing system adapted to be carried by a common carrying means, an object whose position is to be stabilized, said object being pivoted to an object frame along a predetermined axis, said object frame being rotatable on a supporting member about an axis angularly disposed relative to said predetermined axis, a controlled gimbal system, said gimbal system comprising a frame member and a ring member, said ring member being rotatable in said frame member about a frame axis angularly disposed with respect to said ring axis and fixed with respect to said frame member, a transmitting synchro which has two relatively rotatable component parts, said component parts being electrically energized to produce output signal currents which vary in accordance with changes in the angular relation between said component parts, a plurality of receiving synchros, each of which has two relatively rotatable component parts, one of said component parts being supplied with signal currents to establish a predeter-

mined position of said component parts, the other of said component parts producing a signal in accordance with the angular deviation of said last-named component parts from said predetermined position, one of said receiving synchros having one of its component parts rotatable in said ring member about a ring axis fixed with respect to said ring member, means for maintaining the axis, about which the other component part of said last-named synchro is rotatable, fixed in a predetermined direction with variations in the position of said carrying means, means responsive to the output signal of said last-named synchro for driving said frame member to a position of angular agreement between the component parts of said last-named synchro, said transmitting synchro having one of its component parts fixed with respect to said carrying means, and the other of its component parts rotatable with said frame member, another of said receiving synchros having one of its component parts fixed with respect to said supporting member, and the other of its component parts being rotatable with said object frame, the output signal currents of said transmitting synchro being supplied to said last-named receiving synchro, means responsive to the output signal of said last-named synchro for driving said object frame to a position of angular agreement between the component parts of said last-named synchro, and means for supplying position predetermining signal currents to said first-named receiving synchro to predetermine the position of said object.

5. In a position stabilizing system adapted to be carried by a common carrying means, an object whose position is to be stabilized, said object being pivoted to an object frame along a predetermined axis, said object frame being rotatable on a supporting member about an axis angularly disposed relative to said predetermined axis, a controlled gimbal system, said gimbal system comprising a frame member and a ring member, said ring member being rotatable in said frame member about a frame axis angularly disposed with respect to said ring axis and fixed with respect to said frame member, a plurality of transmitting synchros, each of which has two relatively rotatable component parts, said component parts being electrically energized to produce output signal currents which vary in accordance with changes in the angular relation between said component parts, a plurality of receiving synchros, each of which has two relatively rotatable component parts, one of said component parts being supplied with signal currents to establish a predetermined position of said component parts, the other of said component parts producing a signal in accordance with the angular deviation of said last-named component parts from said predetermined position, one of said receiving synchros having one of its component parts rotatable in said ring member about a ring axis fixed with respect to said ring member, means for maintaining the axis, about which the other component part of said last-named synchro is rotatable, fixed in a predetermined direction with variations in the position of said carrying means, means responsive to the output signal of said last-named synchro for driving said frame member to a position of angular agreement between the component parts of said last-named synchro, one of said transmitting synchros having one of its component parts fixed with respect to said carrying means, and the other of its component parts rotatable with said frame member, another

of said receiving synchros having one of its component parts fixed with respect to said supporting member, and the other of its component parts being rotatable with said object frame, the output signal currents of said transmitting synchro being supplied to said last-named receiving synchro, means responsive to the output signal of said last-named synchro for driving said object frame to a position of angular agreement between the component parts of said last-named synchro, another of said transmitting synchros having one of its component parts fixed with respect to said frame member, and the other of its component parts rotatable with said ring member, another of said receiving synchros having one of its component parts fixed with respect to said object frame and the other of its component parts rotatable with the rotation of said object about said predetermined axis, the output signal currents of said last-named transmitting synchro being supplied to said last-named receiving synchro, means responsive to the output signal of said last-named synchro for driving said object to a position of angular agreement between the component parts of said last-named synchro, and means for supplying position predetermining signal currents to said first-named receiving synchro to predetermine the position of said object.

6. In a position stabilizing system adapted to be carried by a common carrying means, a controlled gimbal system, said gimbal system comprising a reference member, a main ring member, an auxiliary ring member and a frame member, said reference member being rotatable in said main ring member about a main ring axis fixed with respect to said main ring member, said main ring member being rotatable in said auxiliary ring member about an auxiliary ring axis angularly disposed with respect to said main ring axis and fixed with respect to said auxiliary ring member, said auxiliary ring member being rotatable in said frame member about a frame axis parallel to said auxiliary ring axis and fixed with respect to said frame member, means for setting said auxiliary ring member in a predetermined angular relationship with respect to said main ring member, said gimbal system having a reference axis formed by the intersection of two planes lying respectively along said main ring and frame axes and fixed respectively with respect to said main ring and frame members, and means for maintaining said reference axis in a predetermined direction with variations in the position of said carrying means.

7. In a position stabilizing system adapted to be carried by a common carrying means, an object whose position is to be stabilized, said object being movable about two axes angularly disposed relative to each other, a controlled gimbal system, said gimbal system comprising a reference member, a main ring member, an auxiliary ring member and a frame member, said reference member being rotatable in said main ring member about a main ring axis fixed with respect to said main ring member, said main ring member being rotatable in said auxiliary ring member about an auxiliary ring axis angularly disposed with respect to said main ring axis and fixed with respect to said auxiliary ring member, said auxiliary ring member being rotatable in said frame member about a frame axis parallel to said auxiliary ring axis and fixed with respect to said frame member, means for setting said auxiliary ring member in a predetermined angular relationship with respect to said main ring member,

said gimbal system having a reference axis formed by the intersection of two planes lying respectively along said main ring and frame axes and fixed respectively with respect to said main ring and frame members, means for maintaining said reference axis in a predetermined direction with variations in the position of said carrying means, and driving means responsive to the movement of said auxiliary ring member relative to the frame member about the frame axis for moving said object about one of its axes through an angle substantially equal to the angle of motion between said auxiliary ring member and said frame member.

8. In a position stabilizing system adapted to be carried by a common carrying means, an object whose position is to be stabilized, said object being movable about two axes angularly disposed relative to each other, a controlled gimbal system, said gimbal system comprising a reference member, a main ring member, an auxiliary ring member and a frame member, said reference member being rotatable in said main ring member about a main ring axis fixed with respect to said main ring member, said main ring member being rotatable in said auxiliary ring member about an auxiliary ring axis angularly disposed with respect to said main ring axis and fixed with respect to said auxiliary ring member, said auxiliary ring member being rotatable in said frame member about a frame axis parallel to said auxiliary ring axis and fixed with respect to said frame member, means for setting said auxiliary ring member in a predetermined angular relationship with respect to said main ring member, said gimbal system having a reference axis formed by the intersection of two planes lying respectively along said main ring and frame axes and fixed respectively with respect to said main ring and frame members, means for maintaining said reference axis in a predetermined direction with variations in the position of said carrying means, driving means responsive to the movement of said auxiliary ring member relative to the frame member about the frame axis for moving said object about one of its axes through an angle substantially equal to the angle of motion between said auxiliary ring member and said frame member, and driving means responsive to a change in the angular position of the projection of said main ring axis upon a plane substantially at right angles to the reference axis for moving said object about the other of its axes through an angle which is equal to the change in the angular position of said projection.

9. In a position stabilizing system adapted to be carried by a common carrying means, an object whose position is to be stabilized, said object being pivoted to an object frame along a predetermined axis, said object frame being rotatable on a supporting member about an azimuth axis angularly disposed relative to said predetermined axis, a controlled gimbal system, said gimbal system comprising a reference member, a main ring member, an auxiliary ring member and a frame member, said reference member being rotatable in said main ring member about a main ring axis fixed with respect to said main ring member, said main ring member being rotatable in said auxiliary ring member about an auxiliary ring axis angularly disposed with respect to said main ring axis and fixed with respect to said auxiliary ring member, said auxiliary ring member being rotatable in said frame member about a frame axis parallel to said auxiliary ring axis and fixed with re-

spect to said frame member, means for setting said auxiliary ring member in a predetermined angular relationship with respect to said main ring member, a plurality of transmitting synchros, each of which has two relatively rotatable component parts, said component parts being electrically energized to produce output signal currents which vary in accordance with changes in the angular relation between said component parts, a plurality of receiving synchros, each of which has two relatively rotatable component parts, one of said component parts being supplied with signal currents to establish a predetermined position with respect to said component parts, the other of said component parts producing a signal in accordance with the angular deviation of said last-named component parts from said predetermined position, one of said receiving synchros having one of its component parts rotatable in said main ring member about a main ring axis fixed with respect to said main ring member, means for maintaining the axis about which the other component part of said last-named synchro is rotatable, fixed in a predetermined direction with variations in the position of said carrying means, means responsive to the output signal of said last-named synchro for driving said frame member to a position of angular agreement between the component parts of said last-named synchro, one of said transmitting synchros having one of its component parts fixed with respect to said carrying means, and the other of its component parts rotatable with said frame member, another of said receiving synchros having one of its component parts fixed with respect to said supporting member, and the other of its component parts being rotatable with said object frame, the output signal currents of said transmitting synchro being supplied to said last-named receiving synchro, means responsive to the output signal of said last-named synchro for driving said object frame to a position of angular agreement between the component parts of said last-named synchro, another of said transmitting synchros having one of its component parts fixed with respect to said frame member, and the other of its component parts rotatable with said auxiliary ring member, another of said receiving synchros having one of its component parts fixed with respect to said object frame and the other of its component parts rotatable with the rotation of said object about said predetermined axis, the output signal currents of said last-named transmitting synchro being supplied to said last-named receiving synchro, and means responsive to the output signal of said last-named synchro for driving said object to a position of angular agreement between the component parts of said last-named synchro.

10. An angle computer comprising a gimbal system, said gimbal system comprising a frame member and a ring member, a receiving synchro, which has two relatively rotatable component parts, one of said component parts being supplied with signal currents to establish a predetermined position of said component parts, the other of said component parts producing a signal in accordance with the angular deviation of said last-named component parts from said predetermined position, said receiving synchro having one of its component parts rotatable in said ring member about a ring axis fixed with respect to said ring member, means for attaching the other of said component parts to a position stabilizing

means, means responsive to the output signal of said last-named synchro for driving said frame member to a position of angular agreement between the component parts of said last-named synchro, a plurality of transmitting synchros, each of which has two relatively rotatable component parts, said component parts being electrically energized to produce output signal currents which vary in accordance with changes in the angular relation between said component parts, one of said transmitting synchros having one of its component parts fixed with respect to said carrying means, and the other of its component parts rotatable with said frame member, another of said transmitting synchros having one of its component parts fixed with respect to said frame member, and the other of its component parts rotatable with said ring member.

11. An angle computer comprising a gimbal system, said gimbal system comprising a reference member, a main ring member, an auxiliary ring member and a frame member, said reference member being rotatable in said main ring member about a main ring axis fixed with respect to said main ring member, said main ring member being rotatable in said auxiliary ring member about an auxiliary ring axis angularly disposed with respect to said main ring axis and fixed with respect to said auxiliary ring member, said auxiliary ring member being rotatable in said frame member about a frame axis parallel to said auxiliary ring axis and fixed with respect to said frame member, means for setting said auxiliary ring member in a predetermined angular relationship with respect to said main ring member, and means for attaching said reference member to a position stabilizing means.

12. An angle computer comprising a gimbal system, said gimbal system comprising a main ring member, an auxiliary ring member and a frame member, said main ring member being rotatable in said auxiliary ring member about an auxiliary ring axis angularly disposed with respect to said main ring axis and fixed with respect to said auxiliary ring member, said auxiliary ring member being rotatable in said frame member about a frame axis parallel to said auxiliary ring axis and fixed with respect to said frame member, means for setting said auxiliary ring member in a predetermined angular relationship with respect to said main ring member, a plurality of transmitting synchros, each of which has two relatively rotatable component parts, said component parts being electrically energized to produce output signal currents which vary in accordance with changes in the angular relation between said component parts, a receiving synchro which has two relatively rotatable component parts, one of said component parts being supplied with signal currents to establish a predetermined position with respect to said component parts, the other of said component parts producing a signal in accordance with the angular deviation of said last-named component parts

from said predetermined position, said receiving synchro having one of its component parts rotatable in said main ring member about a main ring axis fixed with respect to said main ring member, means for attaching the other of said component parts to a position stabilizing means, means responsive to the output signal of said last-named synchro for driving said frame member to a position of angular agreement between the component parts of said last-named synchro, one of said transmitting synchros having one of its components parts fixed with respect to said carrying means, and the other of its component parts rotatable with said frame member, another of said transmitting synchros having one of its component parts fixed with respect to said frame member, and the other of its component parts rotatable with said auxiliary ring member.

13. In a position stabilizing system, two gimbal systems, each comprising a frame member, a ring member, and a reference member, said reference member being rotatable in said ring member about a ring axis fixed with respect to said ring member, said ring member being rotatable in said frame member about a frame axis angularly disposed with respect to said ring axis and fixed with respect to said frame member, the reference member of one of said gimbal systems carrying two parallel arms spaced from each other, the reference member of the other of said gimbal systems carrying a single arm of the same length as said parallel arms, a triangular member rotatably connected at its apices to each of said three arms for holding said reference members in predetermined orientation with respect to each other.

14. In a position stabilizing system, a reference position determining device, a gimbal system, a common support for said position determining device and said gimbal system, and a signal generator including relatively rotatable, coaxial stator and rotor members, one of said members being supported in said gimbal system, and the other being linked to said position determining device and, by said link, fixed against rotation with respect to said device, whereby tilting of said support, in a plane other than mutually perpendicular planes which include the pivots of said gimbal system and the axes of said stator and rotor members, results in relative rotation between said stator and rotor members and the generation of a position correcting signal.

JOHN W. DAWSON.
